MULTIPLE PANED WINDOW

Filed July 5, 1927

INVENTOR
Raymond H. Starr
BY MURRAY B. ROMM

ATTORNEY

UNITED STATES PATENT OFFICE

RAYMOND H. STARR, OF NORTH KANSAS CITY, MISSOURI

MULTIPLE-PANED WINDOW

Application filed July 5, 1927. Serial No. 203,411.

My invention relates to multiple paned windows and method of installing the same, and has for its object the sealing of the panes to insulate the spaces between panels, and the withdrawal of moisture from said spaces.

In accomplishing these objects I have provided improved details of structure, the preferred forms of which are illustrated in the accompanying drawings, wherein:

10 Fig. 1 is a perspective view of a display case equipped with windows constructed in accordance with my invention, the glass panels shown in section.

Fig. 2 is a sectional view of the lower portion of a window installed in the frame of a case.

Fig. 3 is a detail sectional view of the sealing medium.

Fig. 4 is a detail sectional view illustrating the method of installing a glazing strip.

Fig. 5 is a detail sectional view illustrating the method of completing the installation of a sealing element.

Referring in detail to the drawings: 25 1 designates a show case, in this instance a refrigerating display case being illustrated for which multiple panel windows are usually provided whereby the frosting of the panes due to moisture condensed thereon may be 30 minimized.

2 designates a window frame, 3 an upper and 4 a lower casing thereof in which glass panels 5, 6 and 7 are to be installed. Three panels are here illustrated though the number 35 may vary.

A back stop 8 of the lower casing is illustrated as a stop produced by the rabbeting of the casing to produce a groove 9 in which the panels are to be positioned. A similar back 40 stop 10 is associated with the upper casing 3 and it is understood that the sides or ends of the frame or opening of the show case are similarly constructed.

A sealing element 11 which represents a 45 particular feature of my invention and is designed to provide a flexible setting for the glass, is spread in the groove of the casing, and an upturned portion 12 is arranged in contact with the back stop 8, for convenience 50 the installation of the window portions in the

lower casing being discussed. The sealing element comprises a plastic, flexible and adhesive substance preferably having uncured rubber or similar material as a base, and having relatively permanent resilient and adhesive qualities. A substance of the suggested composition is provided that will continue to adhere to both glass and wood and will preserve its sealing function under conditions of expansion and contraction of the glass and 55 wood.

The plastic material is laid in the casing grooves of top and ends also, to the thickness desired, for example, $\frac{1}{8}$ inch, and against the faces of the back stops on the inner edge of 60 the frame, the glass panel 5 is positioned in contact with the upturned edge 12 and the body portion of the sealing element.

Glazing strips or separators, such as 13 and 20 14, are positioned in contact with the sealing element and the surfaces of the panel 5 adjacent its outer edges, and the second panel 6 is installed in contact therewith whereby a chamber or enclosed space 15 is produced. A 25 second glazing strip, such as 16, is installed 70 as the separator between the second panel 6 and the third panel 7, the glazing strip being positioned by a process illustrated in Fig. 4, to which special attention is called. The strip is held slantingly and its edge is pressed 75 into the substance of the plastic material adjacent the edge of the panel 6; the strip is then pressed and established in horizontal position, whereby a portion 18 of the plastic element 11 is pinched and protruded upwardly 80 to constitute a flange or extension of the sealing element between the panel and the strip. The strips may be secured to the frame 85 by nails 19 in process of installation.

The panel 7, which is the outer panel, having 90 been positioned, the free edge of the sealing element is pressed upward as illustrated in Fig. 5, and laid against the outer face of the glass to produce the flange 20; and a finish 95 stop 21 is installed to press the flange 20 in position and retain it, and to hold the assembled window in position. It is understood that similar treatment of the sealing element 11 occurs with reference to the top and sides 100 of the window to enclose and seal all edges.

of the outer panel, and finish stops are similarly installed.

A dehydrating element is provided comprising a hygroscopic substance designated 5 22 which is deposited, during the installation of the window elements, in recesses 23 in the glazing strips, and cover members 24 having perforations 25 are positioned over the hygroscopic substance to retain the 10 same while permitting the functioning thereof through said openings.

The structure having been provided as described, the sealing element insulates the spaces enclosed by the panels and strips so 15 that moisture may not enter therein through the pores of the wood of the frame or around the edges of the glass panels, and exterior moisture is also retained away from the glazing strips which might conduct moisture into 20 the spaces. Such moisture as may have been present in the air trapped by the panels on initial establishment thereof, is attracted and withdrawn from the spaces by the hygroscopic element. The spaces being devoid of 25 moisture, there is no condensation on the surfaces of the panes within the enclosed space and therefore, no frosting of the panels to obstruct the view therethrough.

The character of the sealing element which 30 I designate is such that it is permanently able to maintain the seal. It is provided as having permanent tensile strength so that a relatively large area may be laid and will preserve its integrity under distortion, and 35 will yield to expansion of the panels; and, being relatively permanently viscous and retaining over a long period the quality of adhesiveness, and also having a substantial degree of elasticity that persists, will maintain its contact with the contracting panels. 40 Should accident result in chance introduction of moisture to the spaces, the hygroscopic element will absorb the moisture therefrom.

45 I particularly provide the indicated shield or cover for the hygroscopic element in view of the preferable use of an element in powdered form, portions of which might be imperceptibly scattered, to be deposited on the 50 inner surfaces of the panels, there to absorb moisture and so eventually become objectionably visible. The material may be provided in a cloth bag or similar container, and supplemental means may be used as desired, to 55 protect the material from disturbance during installation.

What I claim and desire to secure by Letters Patent is:

1. In a window, a frame having a rabbeted 60 edge, a sealer comprising plastic material disposed in the frame to receive the edges of glass panels, a plurality of panels having edges contacting said plastic material, glazing strips spacing said panels, means securing 65 the strips to the frame to fix the panels.

in position, portions of said plastic material being deflected between one of said strips and one of said panels, and a portion of said plastic material being upturned against the outer side of the outermost of said panels, and a stop fixed to the frame and engaging said last-named portion of plastic material with said outer panel side. 70

2. In a window, a frame having a rabbeted edge, a sealer comprising plastic material disposed in the frame to receive the edges of glass panels, a plurality of panels positioned in said plastic material, glazing strips spacing said panels, portions of said plastic material being distorted over adjacent face portions of the panels, and means fixing the panels in position. 75

3. In combination with a grooved window frame, a plurality of spaced panels, means for sealing the spaces between the panels 85 comprising a flexible element positioned in the groove of the window frame to receive the edges of the panels, a separator whereby a portion of the flexible element is pinched into position between a panel and said separator in the process of positioning said separator, and means for fixing the separator and panels in position. 90

4. In a device of the character described, a frame having a rabbeted edge, a sealer comprising plastic material covering the inner surface of the frame and extending continuously circumferentially and transversely thereof, a plurality of panels positioned in the frame with their circumferential edges 100 engaging the plastic material, means spacing said panels, portions of said plastic material being distorted over outer adjacent free portions of the panels, and means fixing the panels in position. 105

In testimony whereof I affix my signature.

RAYMOND H. STARR.
